Term of patent 14 years

Int. Cl. D14—02

U.S. Cl. D26—5 C

FIG. 1 is a perspective view of an acoustic coupled remote data entry terminal showing our new design.

FIG. 2 is a front elevational view thereof.

FIG. 3 is a rear elevational view thereof.

FIG. 4 is a side elevational view thereof, the opposite side being substantially identical thereto.

FIG. 5 is a top plan view thereof.

The broken line disclosure of the numerals in FIGS. 1 and 5 is for illustrative purposes only and forms no part of the claimed design. The power cord has been shown fragmentarily in FIGS. 3, 4 and 5 for convenience of illustration.

We claim:

The ornamental design for an acoustic coupled remote data entry terminal or similar article, as shown and described.
